GARMENT

Bertrand Rabbiner, Brooklyn, N. Y., assignor to
 Aero-Bocker Knitting Mills, Inc., New York,
 N. Y., a corporation of New York

Application April 29, 1938, Serial No. 204,985

3 Claims. (Cl. 2—228)

This invention relates to garments, and more particularly to improvements in knitted cuffs applied to garments such as "ski-pants".

Ski-pants are provided ordinarily with a knitted cuff which is attached to the bottom of each leg and adapted to fit snugly about the ankle. Style is an important factor in such garments, and the accepted style requires that the pants fold over in a bloomer effect uniformly around the cuff. Since the cuffs are tight, it is difficult to insert and remove the foot unless an opening is provided, and numerous attempts have been made heretofore to apply hookless fasteners or "zippers" to such cuffs, so that they may be opened and closed readily to facilitate the insertion of the foot through the cuffs. In applying such hookless fasteners, it has been customary to cut the knitted cuff and to apply the fastener thereto, extending it also beyond the cuff to an opening provided in the fabric of the pants. Also, it has been customary to sew the knitted cuff in a straight line to the bottom of the fabric forming the leg of the pants. This construction introduces stiffness in the fastening device, and causes the leg of the pants to fold in an awkward manner, it being impossible to achieve in this way the desired bloomer effect, and consequently the satisfactory styling of the pants. Efforts to avoid this disadvantage in applying fasteners to the cuffs have not been successful heretofore.

There is a further difficulty inherent in the construction heretofore employed, in that the operations required to attach the fastener to both the cuff and the fabric of the pants requires a number of complicated sewing operations. Thus, instead of sewing directly around the seam which joins the knitted fabric to the fabric of the pants, it has been necessary to stop the sewing at the fastener, apply the tape of the fastener to the fabric of the pants by a different type of operation, and then complete the sewing with a third operation, in order that the fastener may be secured to the fabric. Considerable difficulty is experienced in producing a satisfactory garment, and the cost is excessive.

It is the object of the present invention to provide a method of applying fasteners to knitted cuffs and to secure the cuffs with the fastener to the pants in such a way as to ensure proper and satisfactory draping, that is, the provision of the desired bloomer effect.

Another object of the invention is to facilitate the application of the cuff with the fastener to the pants by a simpler operation which is less

expensive than the procedure heretofore employed.

Another object of the invention is the provision of garments having knitted cuffs with fasteners so applied as to provide the desired bloomer draping of the fabric.

Other objects and advantages of the invention will be apparent as it is better understood by reference to the following specification and the accompanying drawing, in which

Fig. 1 is a sectional view of the lower end of the pants leg with the cuff and closure applied, illustrating the proper and desired draping of the fabric to afford a satisfactory bloomer effect;

Fig. 2 is a similar view with the leg and cuff extended to illustrate the mode of applying the cuff and the fastener;

Fig. 3 is a plan section showing the interior of the pants leg with the cuff applied thereto;

Fig. 4 is a side elevation of the pants leg extended with the cuff and fastener applied;

Fig. 5 is an elevation illustrating the method of cutting the cuff before it is applied to the pants leg;

Fig. 6 is a similar view illustrating the shaping of the pants leg to which the cuff is applied; and

Fig. 7 is an elevation of the familiar hookless fastener or "zipper".

In carrying out the invention, I have discovered that the proper draping of the fabric depends upon the initial shaping of the abutting edges of the pants leg and cuff and the elimination of any opening in the fabric of the pants leg to which a fastener must be applied. In other words, I have achieved the desired draping effect by removing from the upper edge of the cuff surplus material which has heretofore interfered with the proper draping, and by cutting the lower edge of the pants leg so as to properly fit the cuff with the surplus material removed. I use, furthermore, a shorter closure which is applied only to the open edges of the cuff and does not extend into any opening in the fabric of the pants leg. With this novel construction, the proper draping is facilitated, and the elimination of the fastener as a stiffening element of the pants leg ensures the draping as shown in Fig. 1 of the drawing instead of the distorted effect which characterizes the attempts made heretofore to apply fasteners to knitted cuffs used in connection with garments such as I have described.

While the construction is simple, it involves a marked change and improvement over the constructions which have been available heretofore,

and provides a garment with satisfactory styling.

Referring to Fig. 1 of the drawing, which shows the draping of the pants leg, 5 indicates the material of the pants leg and 6 the knitted cuff which is secured by stitching to the pants leg along a dotted line 7. The fastener 8 is applied in the usual manner to the edges of the knitted cuff 6, which is cut to permit the insertion of the fastener. This operation is prior to attachment to the pants leg. A slide 9 is adapted to close or open the fastener as may be desired.

In forming the garment, the lower edges of the pants leg 5 are cut in arcs indicated at 10 with flattened edges 11 which are adapted to 15 co-operate with similar edges 12 of the knitted cuff 6. The dotted line 13 indicates the upper edge of the cuff as it comes from the knitting machine, and heretofore has been used as approximately the line of sewing in attaching the 20 cuff to the leg of the garment. In accordance with the present invention, the material between the line 13 and the line 12 is eliminated, so that when the cuff and pants leg are sewed together the stitching follows approximately the line 14, 25 surplus fabric being cut away during the sewing operation by a knife provided for that purpose on the sewing machine (not shown). It will be understood of course, that the cuff is circular in form and that there are, therefore, two edges 30 corresponding to the line 12 opposite each other to co-operate with similar edges at the bottom of the pants leg.

This is more clearly illustrated in Figs. 3 and 4, in which the leg 5 and cuff 6 are shown attached, 35 the lines 14 of sewing extending upwardly to points 15 at the sides of the leg. The fastener 8 with its slide 9 is attached to a tape 16 which is sewed to the edges of the cuff 6. The tape extends upwardly only to the point 15 and consequently the fastener is engaged with the material of the pants leg only at the point where the knitted cuff is likewise engaged. The fastener consequently does not intend to stiffen the fabric of the pants leg as has been usual in constructions heretofore used. The present construction 40 facilitates the joining of the cuff to the pants leg because the sewing machine can work completely around the abutting edges of the knitted fabric and the pants leg without encountering metal which would, of course, break the needles. Furthermore, the difficult operations required to 45 extend the fastener between edges of the material forming the pants leg are entirely avoided in the application of the cuff according to the present invention. A special advantage of the construction described is that the upper edge of the knitted cuff stretches readily to the full width of the pants leg. This avoids extreme gathering and permits the desired drape effect which distinguishes the invention from the construction 50 heretofore used.

The cuff 6 may be a double fabric, that is to say, it may be knitted so as to be turned to provide two layers of knitting, or it may be a single 55 selvage welt cuff. Any suitable knitted construction may be employed, provided it has the

desired elasticity and other advantages of knitted cuffs for the purpose. No special machines or arrangements are required to produce cuffs adapted to be employed in accordance with the present invention. They are knitted in the ordinary manner, and thereafter the surplus material is cut away as indicated clearly in Fig. 5, and as hereinbefore described, in order to provide the arc-shaped edges which facilitate attachment to the pants leg and afford the desired 10 draping effect and the elimination of awkward or ugly folds which destroy the desired styling of the finished product.

Moreover, as hereinbefore indicated, the structure as described facilitates the manufacturing 15 operations, eliminating unnecessary and complicated stitching operations and affording with a stronger construction which is less likely to rip or tear. Because of the elimination of stiffness due to insertion of the fastener in the relatively 20 heavier fabric of the pants, the operation of the fastener is made more easy, and the user finds the garment more comfortable than similar garments constructed in the manner heretofore followed. The provision of the fastener permits 25 opening of the cuff so that the wearer can put on or remove the garment without removing the shoes.

Various changes may be made in the form and arrangement of the parts and details of construction thereof, without departing from the 30 invention or sacrificing any of its advantages.

I claim:

1. A garment having legs each provided with a cuff at its bottom of narrower width than the leg, the lower edge of each leg proper having at least one recess extending upwardly from its lower edge, each cuff having an extension projecting upwardly into the recess of the leg to which it is attached and having an opening 40 extending upwardly from its lower edge into but not beyond its said extension, and fasteners affording closures for the opening in the cuffs.

2. A garment having legs each provided with an elastic cuff at its bottom of narrower width than the leg, the lower edge of each leg proper having at least one recess extending upwardly from its lower edge, each cuff having an extension projecting upwardly into the recess of the leg to which it is attached and having an opening 45 extending upwardly from its lower edge into but not beyond its said extension, and fasteners affording closures for the opening in the cuffs.

3. A garment having legs each provided with a cuff of knitted fabric at its bottom of narrower width than the leg, the lower edge of each leg proper having recesses with upwardly converging sides, each cuff having extensions projecting into the recesses of the leg to which it is attached and having the edges thereof secured to the edges of said recesses, each cuff having an opening extending upwardly from its lower edge to a point adjacent the uppermost part of an extension thereof, and fasteners affording closures for the openings in the cuffs.

BERTRAND RABBINER.
